UNITED STATES PATENT OFFICE.

JAMES MILLARD, OF STEUBENVILLE, OHIO.

GATE.

Application filed June 22, 1926. Serial No. 117,725.

The invention relates to improvements in gates and has particular reference to what is commonly known as a farm gate.

The principal object of the invention is 5 the provision of a gate having the vertical posts and the longitudinal bars pivotally secured to one another so as to permit adjustment of the outer end of the gate upwardly and parallelogrammatically, and to 10 provide means to hold the gate in adjusted positions, said means comprising a pair of bars secured on the gate and pivotally engaging one of the horizontal bars and having ends extended above and below the gate 15 joined by screw bolts or other adjusting members to clamp the bars in engagement with the horizontal bars when the gate is adjusted to hold the gate in the position to which it has been adjusted, the lower 20 end of a pair of bars also serving when the gate is in its lowermost position to support the outer end of the gate and prevent it sagging.

The invention will be described in detail 25 hereinafter and will be found illustrated in the accompanying drawings, in which

Figure 1 is a side view of the improved gate showing it in its lowermost position in full lines and in one of its adjusted positions in broken lines, and

Figure 2 is a vertical sectional view on a plane indicated by the line 2-2 of Figure 1.

In the drawings similar reference characters will be used to designate corresponding parts throughout both of the views.

The improved gate comprises end posts 1 and 2, horizontal bars 3 having their ends pivotally secured to the end posts 1 and 2 40 by means of pivot pins or bolts 4 and intermediate of the end posts 1 and 2 is a vertical member 5 comprising a pair of bars one on each side of the horizontal bars 3 and pivotally engaging said horizontal bars 45 by means of pivot pins or bolts 6. A clamping member is provided and designed to hold the gate in adjusted positions and comprises another pair of bars designated 7, and pivotally engaging one of the horizontal bars 3 by means of a pivot pin or bolt 8, the bars 7 being elongated and having their ends extended above and below the gate as shown and 9 indicates bolts or other clamping members connecting the extended 50 ends of the bars 7 and adapted to hold the bars in clamped position in engagement

with the horizontal bars 3 to hold the gate in adjusted position. Furthermore, the lower extension of the bars 7 serves to support the gate when it is in its lowermost 60 position to prevent sagging.

The gate is adapted to be hinged to a hinge post 10 or other suitable support by engaging the end post 1, it being understood that any type of hinge may be employed. 11 65 indicates a latch post, and 12 designates a sliding latch mounted between two of the horizontal bars 3 and adapted to extend through an opening in the end post 2 of the gate to engage the latch post. 70

It will be readily apparent that the material of which the gate is constructed is an immaterial feature of the invention as the parts of the gate may be of timber or of metal, and may preferably be made of 75 metal tubing.

The advantage of the gate hereinbefore described is that any obstructions, such for instance as deep snows may be overcome by swinging the gate into the position shown in broken lines in Figure 1, and also the gate may be adjusted in the position shown in broken lines to permit small stock such as hogs, sheep, and the like to go from field to field but will not permit larger stock 85 such as cattle and horses to pass through.

What is claimed is:—

A gate, comprising end posts, longitudinal bars pivotally engaging said end posts, a pair of bars pivotally engaging said longitudinal bars intermediate of the end posts by pivots extending therethrough and through each of said pair of bars, another pair of bars arranged on the two sides of said longitudinal bars and pivotally secured to one of said longitudinal bars, said pair of bars extended above and below the gate, bolts secured to the extended ends of said pair of bars and adapted to clamp said bars in frictional engagement with the longitudinal bars, the gate being adapted to be adjusted parallelogrammatically to avoid obstructions thereunder and to be held in adjusted positions by clamping said pair of bars in engagement with the longitudinal bars, and the extended ends of said last mentioned pair of bars, below the gate, forming a support for the gate in its lowest position.

In testimony whereof I affix my signature.

JAMES MILLARD.
